H. C. MALLORY

ENGINE COOLING SYSTEM

Original Filed May 17, 1923

INVENTOR
HARRY C. MALLORY
BY
John E. Herbold
ATTORNEY

UNITED STATES PATENT OFFICE.

HARRY C. MALLORY, OF NEW YORK, N. Y.; SUE R. MALLORY ADMINISTRATRIX OF
SAID HARRY C. MALLORY, DECEASED.

ENGINE-COOLING SYSTEM.

Application filed May 17, 1923, Serial No. 639,505. Renewed July 9, 1925.

To all whom it may concern:

Be it known that I, HARRY C. MALLORY, a citizen of the United States, and resident of New York city, in the county of New York and State of New York, have invented certain new and useful Improvements in Engine-Cooling Systems, of which the following is a specification.

My present invention relates to internal combustion engine cooling systems of the boiling and condensing type in which, as in ordinary automobile use, the top of the condenser is above and the bottom of the condenser is below the liquid level maintained in the engine cooling jacket, so that the liquid of condensation will not drain from the bottom of the condenser into the engine jacket as required to keep the latter supplied with water and to avoid an undesirable accumulation of water in the condenser; and the object of my invention is to provide simple and effective means for passing liquid from the condenser back into the jacket without requiring the use of the ordinary liquid return pump heretofore employed for that purpose.

To attain the object of my invention, I provide a steam ejector in the connection through which the vapor formed in the engine cooling jacket passes into the condenser, and utilize the energy available in the vapor passing through the ejector to effect the desired feed of the cooling liquid from the condenser back into the engine cooling space. Preferably I do not require the ejector to handle all the liquid passed from the condenser into the cooling space, but employ a special form of condenser comprising a water holding space in the condenser at the proper level to feed the cooling jacket by gravity, and provide for a liquid overflow from said space to the hotwell at the bottom of the condenser which thereby fixes the height of water level in the jacket. This water holding space is arranged to collect the liquid of condensation formed in the portion of the condenser above it, and the liquid discharged into the condenser in liquid form by the ejector.

Advantageously the cooling system is of

the type disclosed and claimed in my prior Patent No. 1,424,664, granted August 1, 1922, in which a constant pressure in the condenser, and an approximately constant boiling temperature in the jacket, are maintained by passing air into and withdrawing it from the condenser to correspondingly vary the capacity of the condenser. When the present invention is utilized in the cooling system of my prior patent, a large portion of the vapor passed into the condenser will be condensed in the upper portion of the latter, under all conditions, and under light load conditions when the vapor passing through the ejector is relatively small in amount, and the water lifting capacity of the ejector is correspondingly reduced, the ejector needs to pass but little, if any, liquid in order to prevent an undue lowering of the liquid level in the jacket.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described preferred embodiments of my invention.

Of the drawings:

Fig. 1 is an elevation with parts broken away and in section of one form of my improved cooling system;

Fig. 2 is a section on the line 2—2 of Fig. 1;

Fig. 3 is a sectional elevation of the steam ejector employed; and

Fig. 4 is a partial section taken similarly to Fig. 2 illustrating a modified construction.

In the drawings and referring first to the construction shown in Figs. 1 and 2, A represents the cooling liquid jacket for the cylinders A⁵ of an ordinary internal combustion automobile engine. An inlet A' is provided at the bottom of the jacket space for the cooling liquid which will ordinarily be water or a water and alcohol mixture, and A² represents an outlet for vapor from the top of the jacket. The vapor outlet A²

is connected to the inlet B' of a condenser B by a conduit which includes an ejector C. The condenser B may be similar in its general dimensions and arrangement to the radiators employed in ordinary automobile liquid circulation cooling systems. It differs from the condensers heretofore devised for automobiles having cooling systems of the boiling and condensing type, in that it is divided into separate upper and lower condensing sections with a water holding pocket or space B^2 at the bottom of the upper condensing section which receives the liquid of condensation formed in the upper section of the condenser as well as the liquid passed into the condenser by the ejector C as hereinafter described. As shown the upper water receiving pocket is formed by a baffle or partition extending across the condenser between the front and rear walls of the condenser shell but having its upturned end portions B^3 spaced away from the side edges of the condenser shell so as not to obstruct the passage of vapor downward into the lower portion of the condenser, and to permit water to overflow from the upper water pocket B^2 into the main condenser hotwell space B' at the bottom of the condenser. Both the upper and lower sections of the condenser are traversed by cooling devices shown as the usual horizontal tubes B^5 having their open ends expanded and soldered or brazed together to form corresponding portions of the front and rear walls of the condenser shell. These tubes are spaced away from the edges of the condenser shell to form steam distributing channels and flow channels for the water overflowing the edges B^3 of the water space B^2 . In the upper section of the condenser the tubes are arranged in two groups separated by a vertical channel beneath the inlet B' , and baffles B^6 may be provided as shown at the opposite sides of this channel to guide liquid entering the condenser through the inlet B' directly into the water space B^2 , while the tubes B^5 are spaced away from the top of the condenser shell to permit the vapor to pass into the top of the upper tube groups and into the upper ends of channels B^6 . In the lower portion of the condenser, tubes B^5 are omitted to provide a central air collecting space B^8 from which air is withdrawn by a conduit D as hereinafter described. Advantageously water sealed baffles B^9 are provided at the bottom of the lower portion of the condenser to further guard against the flow of uncondensed vapor into the air space B^8 . As shown, though this is not essential, inclined baffles or rain plates B^{10} are provided in the lower portion of the condenser to carry water of condensation formed immediately above them to the channels B^8 and thus increase the efficiency of

the portion of the condenser beneath them. As shown, the water space B^2 is provided with two outlets B^{11} , one adjacent each side of the condenser. These outlets are connected by a pipe E from which a branch E' runs to the cooling jacket inlet A'. The outlet port and piping arrangement described permits a ventilating fan F to be arranged as usual, at the rear of the condenser, this fan being driven through the usual gearing from the engine shaft and serving to draw cooling air through the tubes B^3 .

With the described arrangement the position of the overflow edges B^3 of the water space B^2 fixes the height of water level in the cooling jacket A and these edges are arranged at the proper level for that purpose. The water outlet port B^{11} from the condenser hotwell B' is connected by a pipe G to the suction chamber C' of the steam ejector C, which is formed, as shown, with the usual impelling jet nozzle C' and mixing and delivery nozzle C'' separated by an annular space opening at its outer edge to the mixing chamber C. In some cases the pipe G may be provided with a check valve G' as shown to prevent downflow through the conduit. The air pipe D passes through the shell of the condenser and is connected to some external air exhausting means which may be a separate pump, but as shown the desired exhausting effect is obtained by connecting the pipe D to the suction intake manifold A' of the engine. The pipe D may be provided with an automatic air valve D' which closes when heated as it will be by the presence of an undue amount of vapor in the air and vapor mixture withdrawn from the condenser. The cooling system shown is provided with a vacuum relief valve H which automatically opens and admits air to the condenser when the vacuum therein exceeds a predetermined amount. Preferably the valve H is made adjustable in the usual way to permit of regulation of the pressure maintained in the condenser.

In the intended operation of the apparatus disclosed, the passage of the vapor generated in the engine jacket A, to the condenser B through the steam ejector C, creates a minus pressure in the suction chamber C' of the ejector tending to draw water from the condenser hotwell through the conduit G. The liquid thus passed into the condenser through the inlet B' , and the liquid of condensation formed by the condensation of the vapor entering the condenser and condensed above the water space B^2 , is collected by the latter, and passes by gravity through the piping E' and E back into the jacket. When the liquid collects in the space B' at a rate greater than that at which liquid is evaporated

in the jacket, as will be the case with properly designed apparatus under all normal conditions except very light load conditions, the excess liquid overflow into the condenser hotwell and the position of the overflow edges B^3 of the water holding space B^2 thus fix the normal height of liquid level in the jacket. When the cooling system is arranged and operated in accordance 10 with my prior Patent No. 1,424,664, to regulate the capacity of the condenser by varying the accumulation of air in the condenser, the air in the condenser tends to accumulate in the lower portion of the 15 condenser and thereby restrict the condensing capacity of the lower portion of the condenser, so that even under moderately heavy loads the bulk of the condensation will occur in the upper portion of the 20 condenser.

In consequence, the amount of water which must be drawn from the condenser hotwell B^4 by the ejector C to maintain the desired water level in the engine jacket 25 is always comparatively small and reaches its maximum only under maximum load conditions when the amount of vapor passing through the ejector is correspondingly large and the liquid handling capacity of 30 the latter is at a maximum. With a suitably designed ejector the pressure drop through the condenser will be very small and the only effect will be to make the actual water level in the engine jacket A 35 a trifle lower than the water level in the space B^2 .

The water returned to the engine jacket A from the water space B^2 will normally be but little below the temperature of the 40 vapor leaving the jacket, thus tending to uniform temperatures in the jacket at different levels therein. The water drawn from the condenser hotwell through the pipe G will be appreciably cooler than the vapor, so that the water drawn into the 45 ejector will assist materially in condensing the vapor, and thereby correspondingly increases the portion of the liquid collecting in the space B^2 . To avoid all danger 50 of water freezing in the space B^2 when the engine is idle, the latter may be provided with a valve controlled drain, or with a restricted leakage orifice through which 55 the space B^2 will slowly drain into the hotwell, which may be insulated, when the engine is idle. The capacity of the leakage orifice, if used, should be too small, of course, to pass any appreciable portion 60 of the water entering the space B^2 under normal operating conditions.

It will be apparent to those skilled in the art that many changes may be made in the form of the apparatus shown and in particular that the condenser may be modified 65 greatly in form, and one such modification

is illustrated by way of example in Fig. 4. The bottom wall of the upper space B^2 of the condenser BB shown in Fig. 4, is extended at one side of the condenser to close the upper end of one of the side channels B^6 70 and a water sealed baffle B^{12} is provided to prevent vapor from passing into the lower end of that channel to the upper end of which the air exhausting pipe D is connected. The intended operation of the form of apparatus illustrated in Fig. 4 is essentially 75 the same as that illustrated in Figs. 1, 2 and 3. The channel B^6 to which the pipe is connected thus serves as the air collecting space of the condenser. In Fig. 4 the condenser inlet B' is shown as located immediately above the water space B^2 and below the upper condensing section of the condenser. This decreases the height of water lift required from the ejector C . 80

While in accordance with the provisions of the statutes I have illustrated and described the best forms of my invention now known to me, it will be apparent to those skilled in the art that changes may be made 85 in the form of the apparatus disclosed without departing from the spirit of my invention as set forth in the appended claims, and that certain features of my invention may sometimes be used without a corresponding use of other features. 90

Having now described my invention, what I claim as new and desire to secure by Letters Patent, is:

1. In an internal combustion engine of the 100 boiling and condensing type comprising a cooling jacket and a condenser having one portion located above the desired water level in the jacket and another portion including the condenser hotwell located below that 105 level, the improvement which consists in a vapor connection, including a steam ejector provided with a suction chamber, between the upper portion of the jacket and the upper portion of the condenser, a conduit connecting said suction chamber to the condenser hotwell, and means for collecting liquid of condensation formed in the upper portion of the condenser and liquid discharged into the condenser by the ejector, and passing the liquid thus collected by gravity into said cooling space as required to maintain 110 said level. 115

2. In an internal combustion engine cooling system of the boiling and condensing 120 type comprising a cooling jacket and a condenser having one portion located above the desired water level in the jacket and another portion including the condenser hotwell located below that level, the improvement which consists in a vapor connection, including a steam ejector provided with a suction chamber, between the upper portion of the jacket and the upper portion of the condenser, a conduit connecting said suction 125 130

chamber to the condenser hotwell, and liquid discharge into the condenser by the means comprising a water holding space ejector and supplying liquid to said cooling located in the condenser and a gravity dis- space as required to maintain said level. 10
charge therefrom to said jacket and an over- Signed at New York in the county of
5 flow therefrom to the condenser hotwell, for New York and State of New York this 16th collecting liquid of condensation formed in day of May A. D. 1923.
the upper portion of the condenser and HARRY C. MALLORY.
